Julius J. Miller, St. Joseph, Mich.

Application September 27, 1938, Serial No. 231,941

8 Claims. (CL. 217—12)

This invention relates to boxes, and more particularly to those commonly known as wirebound boxes, comprising top and bottom and side walls, and end walls, together with binding wires extending circumferentially of the box to give it strength.

Generally stated, the object of the invention is to provide a novel and improved construction and arrangement whereby the said end walls are detachably fastened to the cleats of the blank from which the box is made, preferably by wire loops inserted through slots cut longitudinally in the ends of two or more of the cleats, so that said loops can be bent into a retaining position externally of the box, and may be bent into engagement with the binding wires, if desired, thus firmly anchoring the loops to the said cleats, but in such a manner that they can be bent back again when it is desired to remove the end walls from the box, after the latter has been opened and relieved of its contents, thus providing a knock-down box unit which can be shipped flat.

It is also an object to provide certain details and novel features of construction tending to increase the general efficiency and desirability of a wirebound box of this particular character.

To the foregoing and other useful ends, the invention consists in matters hereinafter set forth and claimed and shown in the accompanying drawings, in which—

Fig. 1 is a perspective of a wirebound box embodying the principles of the invention, showing the same in closed condition.

Fig. 2 is a transverse section of said box on line 2—2 in Fig. 1, showing the cover or lid of the box partially open.

Fig. 3 is a fragmentary detail section, on a larger scale, on line 3—3 in Fig. 1 of the drawings.

Fig. 4 is a view similar to Fig. 1, with one end of the box shown broken away for convenience of illustration, and with the other end showing a different form of the invention.

Fig. 5 is a horizontal section on line 5—5 in Fig. 4 of the drawings.

Fig. 6 is a fragmentary perspective view of one corner of the box, showing a different form of the invention.

Fig. 7 is a vertical section on line 7—7 in Fig. 6 of the drawings, on a larger scale.

As thus illustrated, and referring to Figs. 1 to 3, inclusive, the invention comprises a box having top and bottom walls 1 and 2, front and rear side walls 3 and 4, and end walls 5, together

with cleats 6 that are stapled to the said top and bottom and side walls by the staples 7 that hold the binding wires 8 in place on the box. The middle binding wire 9 is preferably provided, if the box is of substantial length, to increase the strength thereof.

As shown in said Figs. 1, 2 and 3, it will be seen that the vertical cleats 6, that are fastened to the front and rear side walls 3 and 4, have their upper and lower ends formed with longitudinal cuts 10, and that the said end walls 5 have wire loops 11 that extend through these cuts or slots, and are then bent around and upon the front and rear sides of the box, so that they engage the binding wires 8 previously mentioned. In this way, these wire loops 11 not only removably hold the end walls in position, so that they can be removed when the box is opened and relieved of its contents, but also serve to hold the binding wires in place adjacent the corners of the box, thus preventing said wires from slipping off of the corners. Each end wall is preferably provided with a pair of inside flat battens 12 arranged crosswise of the grain of said end walls, and secured to the latter by staples 13, or other suitable means. The loops 11 are inserted inwardly through the end walls and through their battens 12 and preferably clinched in the battens, as shown in Fig. 3 of the drawings.

Preferably, in this type of box, the binding wires are formed at one end with tongues 14, and at the other end with loops 15, the tongues being adapted to be inserted through the loops and then bent into position to form hooks, as shown in Fig. 1 of the drawings, thereby to hold the cover 1 in closed position, but in such a manner that, by bending said tongues 14 upwardly again, the cover can easily be opened. In the manufacture of box blanks of this kind, comprising sheets of veneer stapled to wood cleats, it is obvious that the staples cannot be allowed to come too close to the corners of the box, and hence when the tongues 11 are bent outwardly and upon the binding wires, the latter are thereby additionally held in place adjacent said corners.

Obviously, the cuts or slots 10 can be inexpensively formed by a saw cut in the ends of the cleats.

In Figs. 4 and 5, the construction is similar to that previously described, but in this case the loops 16 for the end walls are not bent outwardly upon the outer surface of the box, but are bent around to engage the inside or bottom

edges of the cleats 6, as shown, it being observed that by forming the cuts or slots 10 substantially midway between the top and bottom edges of the cleats, the said loops can be bent 5 in either manner, either outwardly upon the outer surface of the box, or inwardly upon the inside or bottom edges of the cleats, the sheets of veneer, forming the top and bottom and side walls of the box, being secured to the outer or 10 top edges of the cleats.

As shown in Figs. 6 and 7 of the drawings, the construction is similar to that shown in Figs. 1 to 3 of the drawings, but in this case the said saw cuts or slots 10 are formed in the top and 15 bottom cleats 6 of the box, so that the loops 11 of the end walls are bent outwardly and around and upon the top or cover of the box, and downwardly and around and upon the bottom of the box. Thus, it is apparent that the cover may have 20 loops for insertion through slots in the front and rear vertical cleats of the box, or through slots in the top and bottom cleats of the box, or through slots in all of the cleats, if so desired. In addition, it is obvious that the loops or tongues 25 thus formed on the end walls can be bent outwardly upon the outer surface of the box to engage the binding wires and hold the latter against slipping off the corners of the box, or that these tongues may be bent inwardly and 30 against the bottom edges of the cleats, for regardless of which way these tongues and loops on the end walls are bent, they serve effectively to anchor the end walls directly to the cleats, and as the latter are stapled to the sheets forming 35 the top and bottom and side walls of the box, it follows that a very strong and simple head or end wall construction is provided. This permits of quick assembly of the box parts when shipped flat, and also permits of quick and easy dismantling of the box after it is opened and relieved 40 of its contents, when it is desired to use the box several times.

Obviously, identically the same end walls can be used in either Fig. 1 or Fig. 4 of the drawings 45 for Fig. 6 of the drawings, as in the latter it is only necessary to turn the end wall around one-quarter, so that the loops thereon will extend through the top and bottom cleats, instead of through the vertical cleats of the head or end 50 wall construction of the box.

Again, it will be noticed that in each form of the invention, the loops, constituting the end wall fasteners, are located close to and practically at the joints between the cleats at the corners of 55 the box, where the greatest strain occurs, and hence these end wall loops or fasteners are especially effective in contributing strength to the structure of the box.

Thus each slot 10 has parallel edges extending 60 longitudinally of the cleat, and each slot has one open end and one closed end, the said open end being at the end of the cleat. In this way, and regardless of which way the flexible fasteners 11 are bent, each fastener will always be bent over 65 one parallel edge of a slot. In this way, there is no mutilation of the inner and outer edges of the cleats, as the slots can be made by cutting longitudinally a distance in the end of the cleat, leaving the longitudinal edges of the cleats unbroken and unmutilated in any way whatever. 70 Thus the outer edge of each cleat presents a smooth and continuous support for one of the sheets of veneer forming the walls of the box.

It is comparatively easy to assemble the box, and the latter is easily taken apart or knocked down for storage or shipment.

Furthermore, it will be seen that each slot 10 has one end thereof open on the end face of its 5 cleat, so that the open end of each slot is closed by the end face of another cleat. In other words, the said slots are not formed in the edges of the cleats, in either the outer or the inner edges thereof, but to the contrary are formed in the 10 ends of the cleats and are thus spaced about midway between said inner and outer cleat edges.

It is important to observe, therefore, that the wire tongues 11 pass through the end walls 5 15 a goodly distance from the edges of the latter and that nowhere do these tongues extend between the top or outer sides of the cleats and the inner surface of the longitudinal walls of the box, while at the same time it is true that each 20 tongue extends through a slot of a cleat.

What I claim as my invention is:

1. A wirebound box comprising sheets forming top and bottom and side walls, cleats and binding wires secured thereto, by staples inserted through the sheets and into the outside edges of the cleats, so that the latter are inside of said walls, with 25 longitudinal slots in said cleats between and parallel with the inner and outer edges thereof, obviating the necessity of any mutilation of said 30 edges in the formation of the slots, the sheets being secured to said outer edges, and end walls provided with flexible metal fasteners for insertion outwardly through said slots, adapted to be bent in position to removably secure the end walls 35 in position within the box, against the inner sides 25 of said cleats, each slot being open at one end thereof on the end face of its cleat, with the open end of each slot closed by the end face of another cleat, when the box is in closed condition.

2. A structure as specified in claim 1, said 40 flexible fasteners being bent outwardly and around and upon the outer surface of the box, to engage the binding wires adjacent the corners of the box, thereby serving to assist in holding said binding wires against slipping off at said 45 corners.

3. A structure as specified in claim 1, said 50 flexible fasteners being bent around and against the said bottom edges of the cleats, adjacent the exposed outer surface of said end walls.

4. A structure as specified in claim 1, said 55 slots being formed in the vertical cleats of the front and rear walls of the box.

5. A structure as specified in claim 1, said 60 slots being formed in the horizontal cleats of the top and bottom walls of the box.

6. A structure as specified in claim 1, each 65 slot being open at its outer end at the beveled end of the cleat.

7. A structure as specified in claim 1, each 70 slot being a straight longitudinal cut closed at one end and open at the other.

8. A box head construction comprising external 75 cleats therefor, with longitudinal slots in the ends of said cleats, parallel with and between the inner and outer edges thereof, one end of each slot being open on the end of its cleat, so that the open end of each slot is closed by the end face of another cleat, and a wall having flexible fasteners extending outwardly through said slots 80 and bent tightly over one parallel edge of the slot to hold said wall in position.

JULIUS J. MILLER.
